ABSTRACT OF THE DISCLOSURE

Continuous monitoring of fluoride effluent by internal electrolysis is accomplished by contacting fluoride containing gas in tubing with an acid electrolyte and the electrolyte then passed through an electrolysis cell having electrodes for spontaneously generating current flow, the electrolyte being introduced by a capillary to form a film on the tubing walls and in which the fluoride is absorbed, the gas being removed and the electrolyte free of gas being passed through the cell and withdrawn, the current flow being measured.

This invention relates to the continuous monitoring of fluoride effluent by internal electrolysis, and more particularly to a process and apparatus for the continuous monitoring of fluoride evolution from a phosphatic fertilizer manufacturing operation or like operation in which gases containing volatile fluorides are produced or discharged into the atmosphere.

A primary object of the invention is to provide a continuous fluoride monitor for the purposes set forth above. Another object is to provide a simple continuous fluoride monitor with remote recording for use in effluent pollution control of phosphate plant emission. A further object is to provide a fluoride monitor device of simple and compact structure which may be utilized in the field and in operating plants for the effective determination and control of fluorides in waste gases, etc. Other specific objects and advantages will appear as the specification proceeds.

The invention is illustrated by a specific embodiment and may be employed in connection with apparatus shown in the accompanying drawing in which FIG. 1 sets out a diagrammatic showing of the apparatus and FIG. 2 is an enlarged vertical sectional view of an electrolysis cell which may be employed.

In the illustration given, an electrolyte material from a reservoir 9 flows by gravity into the tubing 10. The tubing 10 communicates with a T-fitting 11 having a gas inlet projection 12 communicating with a gas inlet tube 13. A capillary in the form of a hypodermic tubing 14 extends through a neoprene seal 15 in the lower portion of tubing 10 and downwardly into the lower portion 16 of the T-fitting and into the mouth of a small diameter tube 17. The tube 17 extends through a seal 18 in the lower fitting portion 16 and upwardly as above described to a point where it receives the outlet end of the hypodermic tubing 14. By this means, electrolyte is fed into the small diameter tube 17 where it is spread out in a thin film on the walls of the tube for intimate contact with the gas which is introduced through pipe 13.

By delivery of the electrolyte directly into the capillary, minimum electrolyte volume is required for absorption of gaseous fluorides to provide maximum response. Also the gas velocity in this scrubber tube 17 increases the flow by producing some aspirating action on the electrolyte flow through the needle.

The proportions of the various parts described above may be varied substantially. However, for the purpose of illustration, the capillary may be one inch of No. 25

2

gauge hypodermic tubing and is sufficient for providing one liter per day flow so that from a five-gallon reservoir the feed rate is sufficient for two weeks of operation. Further, by way of example, the tube 17 to which the needle delivers electrolyte may have a diameter of 0.125" O.D. and an inside diameter of approximately 0.079", which provides good results with a pressure drop of 40 mm. (.75") of mercury at an airflow of 1.5 l./min.

The tube 17 delivers the gas and electrolyte into a treating vessel 19 which may be of any suitable shape or construction. I prefer to employ a treating vessel in the shape of a vertically elongated loop, as shown in the drawing and which comprises a larger tube, as, for example, a tube of 0.375" outside diameter. The tube 17 empties into the upper portion 20 of a treating leg having in the lower portion of the leg an electrolysis cell, designated generally by the number 21. The electrolysis cell is provided with aluminum and platinum electrodes preferably embedded in a plastic, such as polyethylene, etc., tube 22, the aluminum electrode 23 and the platinum electrode 24 being spirally arranged and held by the plastic tube within the enlarged tube 19a. The electrodes communicate with a terminal block 25 from which cables lead to a recorder which may be located at a substantial distance from the treating vessel 19. Since such instruments for measuring the current flow and for recording the same are well known, a further detailed description herein is believed unnecessary.

The opposite leg of the treating vessel 19, namely, vertical leg 26, is provided at a point above the center thereof with a T-fitting 27 having an outlet connection 28 communicating with the outlet tube 29. The outlet tube 29 preferably passes into a receiver 31 through a flow meter 30 and from thence to vacuum. Communicating with the sealed receiver through the pipe 32 is a pump device for maintaining a reduced pressure or vacuum upon receiver 31, as, for example, a dry vane-type air sampling pump.

The electrolyte may be any suitable acid material, such as, for example, dilute acetic acid, and to such acid I prefer to add a wetting agent and a small amount of fluoride. For example, the electrolyte may consist of 6% acetic acid, 0.01% wetting agent, and 0.05 mg./l. of fluoride. By way of example, the reagent may consist of 60 ml./l. of acetic acid, 0.1 ml./l. of Tergitol non-ionic NPX, and 0.5 ml. of 0.01% HF per liter. The water used should be copper-free, either deionized or distilled, and not contacted with copper or brass lines after purification.

OPERATION

In the operation of the process and apparatus, I prefer to maintain a liquid head in the tubing 10 of approximately 12", flow therefrom being regulated by the capillary 14. The electrolyte delivered by the capillary 14 into the small diameter tube 17 is spread out in a thin film on the walls of the tube for intimate contact with the gas and, during the passage through tube 17 before reaching the treating vessel 19, the fluoride content is absorbed in the electrolyte. The gas and electrolyte from the scrubber tube 17 are delivered into the leg 20 of the treating vessel 19 at a substantial distance (preferably about 4") above the electrodes of cell 21. The electrolyte falls into the cell, while the gas (air) separates and flows over the top leg 33 and downwardly into the outlet leg 26, being withdrawn through the outlet tube 29 to the vacuum receiver 31. Thus, the gas by-passes the cell 21 and is vented through the pump (not shown) communicating with the vacuum tube 32. The electrolyte flows through the spirals of the cell by gravity downwardly through leg 20 and thence upwardly through leg 26 to the outlet tube 29. The liquid level in the cell is determined by the location of the

T-fitting 27, and the location is such that all of the electrode spiral is below the cell liquid level. The vertical section of the leg 20 above the cell is important in that it permits liquid build-up, in the event of gas blockage, so as to restore normal operation. This vertical area in the upper portion of the leg 20 prevents electrolyte from bypassing the cell 21 in the case of gas blockage.

The bottom leg 34 of the treating vessel 19 is inclined upwardly toward the leg 26, and the upper leg 33 has generally the same inclination. The top leg portion 33 is designed to drain into the electrode leg 20 and the bottom leg portion 34 aids in causing gas bubbles to flow out after entering this region.

Specific examples illustrative of the process and apparatus may be set out as follows:

EXAMPLE I

An apparatus was set up, as shown in the figure, using a cell employing a coil of aluminum wire embedded in an 0.25" O.D. x 3-4" polyethylene tube, the embedding being done by melting a spiral groove into the tubing with a pitch of approximately four grooves per inch. A platinum wire 24 was similarly arranged. The tubing was mounted within the vertical leg 20 of a treating vessel or tube 19a formed of polypropylene tubing. The recorder was a laboratory recorder. The hypodermic tubing was from 1.25" long 25-gauge hypodermic needle. In the assembly of the electrode spiral, an 0.31" I.D. tubing 19a was slipped over the electrode spiral for assembly.

The electrolyte consisted of 60 ml./l. of an acetic acid, 0.1 ml./l. of Tergitol non-ionic NPX, and 0.5 ml. of 0.01% HF per liter. Calibration of the instrument for response to fluoride may be accomplished by introducing gaseous standards containing fluoride in air or by introducing a metered micro amount of aqueous fluoride or by comparison to the integrated fluoride concentration obtained by absorption of a parallel sample in an impinger. Anhydrous HF is the most convenient in calibrating the instrument for use.

In the test operation, calibration was accomplished by means of a standard prepared by metering air into a polyethylene drum liner and adding the 10-30 ml. of anhydrous HF with a polyethylene syringe. Maximum instrument response is checked by direct introduction of anhydrous HF, with approximately one hour required for complete restoration to base line operation.

Electrolyte was delivered at the rate of 0.3 gallon per 24 hours, with the response for initial time being 0.5 minute and for 90% signal time 5 minutes and for recorder deflection mv. 60. The recorder was located 250 feet from the laboratory, and the instrument showed an immediate response to the fluoride content in the gas being treated.

EXAMPLE II

The process was carried out as described in Example I in a Florida plant operating for the manufacture of triple superphosphate and in connection with a dryer stack. The warm gases from the stack were withdrawn and passed through the apparatus and with an immediate record response showing the varying content of the fluoride in the gases being processed.

While in the foregoing specification I have shown specific embodiments of the invention in considerable detail for the purpose of illustrating the invention, it will be understood that such details may be varied widely by those skilled in the art without departing from the spirit of my invention.

I claim:

1. In a process for continuous monitoring of fluoride effluent by internal electrolysis in which fluoride-containing gas is contacted in a tubing with an acid electrolyte and absorbed by the electrolyte and the electrolyte then passed through an electrolysis cell provided with electrodes for spontaneously generating current flow, the steps of introducing the electrolyte by a capillary to form a film on the

tubing walls, introducing gas containing fluoride and contacting the electrolyte therewith for absorption of the fluoride, removing the gas, and passing the electrolyte free of the gas through said cell, measuring the current flow, and continuously withdrawing electrolyte from said cell.

2. The process of claim 1 in which a vacuum is maintained in communication with the electrolyte entering the cell and the electrolyte leaving said cell.

3. In a process for continuous monitoring of fluoride effluent by internal electrolysis in which fluoride-containing gas is contacted in a tubing with a dilute acid electrolyte and absorbed by the electrolyte and the electrolyte then passed through an electrolysis cell provided with electrodes for spontaneously generating current flow, and current flow measured, the steps of introducing the electrolyte by gravity and under a liquid head through a hypodermic needle into the tubing to form a film on the walls thereof, introducing gas containing fluoride into the tube for contact with the electrolyte-coated walls for absorption by the electrolyte of the fluoride, removing the gas, passing the electrolyte substantially free of the gas through said cell, and continuously withdrawing said electrolyte from said cell.

4. In apparatus for continuous monitoring of fluoride effluent by internal electrolysis, an absorption tube of small diameter, capillary means for introducing a dilute acid electrolyte in a thin film onto the inner walls of said tube, means for introducing gas containing fluoride into said tube for absorption by the electrolyte, a treating vessel generally in the shape of a vertically elongated loop, electrodes in the lower portion of one leg of said vessel forming a cell for spontaneously generating current, means for measuring said current, said tube being attached to said vessel so that its outlet communicates with the upper portion of said vessel above said cell, an outlet tube communicating with the other leg of said vessel at a point aligned with a point on said first leg above said cell, a receiver vessel communicating with said outlet tube, and means for maintaining said receiver and said tube under vacuum.

5. The apparatus of claim 4 in which the two vertical legs of the apparatus are connected by inclined legs of generally parallel inclination.

6. The apparatus of claim 4 in which a T-fitting extends between the inlet to the capillary and the absorption tube and is provided therebetween with an inlet for receiving gas.

7. In a process for continuous monitoring of fluoride effluent by internal electrolysis in which fluoride-containing gas is contacted in a tubing with a dilute acid electrolyte and absorbed by the electrolyte and the electrolyte then passed through an electrolysis cell provided with electrodes for spontaneously generating current flow, and current flow measured, the steps of maintaining the aqueous component of the dilute acid electrolyte substantially free of copper, introducing the electrolyte into the tubing to form a film on the walls thereof, introducing gas containing fluoride into the tubing for absorption by the electrolyte of the fluoride, removing the gas, and passing the electrolyte substantially free of the gas through said cell.
